UNITED STATES PATENT OFFICE.

JOSIAH T. TAYLOR, OF BANGOR, MAINE, ASSIGNEE, BY MESNE ASSIGNMENTS, TO HAVEN SAWYER, OF BANGOR, MAINE.

CASE FOR INCLOSING MEASURING TAPES AND SIMILAR ARTICLES.

Application filed November 6, 1922. Serial No. 599,317.

To all whom it may concern:

Be it known that I, JOSIAH T. TAYLOR, a citizen of the United States, and a resident of Bangor, Penobscot County, State of Maine, have invented certain new and useful Improvements in Cases for Inclosing Measuring Tapes and Similar Articles, of which the following is a specification.

My invention relates to cases for inclosing measuring tapes and other similar articles, and it is designed to provide a case in which the parts are organized into a unitary structure in a new and improved manner and having a protective covering retained in place by the elements of the case itself without the use of thread, glue or other attaching means. Other advantages will appear in the specification.

Cases for inclosing measuring tapes are commonly formed of two halves in the shape of flanged caps of metal, cardboard or other suitable material, and a liner, the two halves being held together with their flanges meeting, forming a round drum-shaped case slightly thicker than the width of the tape to be inclosed. The caps are commonly covered with leather or similar material, the coverings of the caps being sewed together at the edges where the two caps meet. The sewing or fastening together of the coverings serves to hold the caps together if the tape "drum" or "reel" is removed, as well as to retain the coverings in place. The sewing together of the edges of the coverings is an expensive operation and the results are not satisfactory, as the thread frequently gives way, permitting the coverings to come loose while the rest of the case is still serviceable. This is commonly the case when such tapes are used under conditions where they are exposed to moisture, or in machine shops or the like where the thread is apt to become saturated with oil, which rots the thread.

My new form of case is so organized that any stitching or other attaching together of the coverings is dispensed with, the leather or other coverings being retained and made fast by the elements of the case itself. This makes for durability and economy.

I have illustrated in the drawings a selected or preferred embodiment of my invention which will now be described, after which the novel features will be pointed out in the appended claims.

In the drawings, Fig. 1 is a perspective view of the finished product; Fig. 2 is a detailed cross-section thereof on line A—A, Fig. 1; Fig. 3 is a broken elevation of the two caps and the liner; Fig. 4 is a detailed cross-section of the case on line B—B of Fig. 2; and Fig. 5 is a detailed view in perspective of a retaining ear of the case bent over the flange of the liner.

Referring to the drawings, 1 and 2 are the usual caps having flanges 3 and 4. These caps fit together over the liner 5, which is a circular piece of metal, U-shaped in cross-section, of suitable width to fit within the caps and having flanges 7 and 8 projecting inwardly from the edges. The liner and the two caps are cut away in the usual manner at 9 to form the tape opening, which in the finished case is bound with metal as at 10. At 11 on the face of one of the caps is the usual metal binding around the opening for the tape drum. Struck up from the faces of the cap at a plurality of points are the ears 13.

In organizing my new tape case in its preferred form, I first form a leather or other covering 14 around each cap, the coverings being of sufficient size to be folded over and under the cap flanges as shown in Fig. 2. The liner is then made fast or clinched to the front cap (the cap with the hole for the tape drum) by turning back the ears 13 of the cap against the flange of the liner, as shown in Fig. 5. The metal guard 11 is then clinched in around the drum hole in the usual manner. The other cap is then placed in position and clinched to the liner by turning back the ears 13 against the other side flange of the liner by means of a screw driver or other suitable tool inserted through the drum hole. The liner 5 and the ears 13 draw and hold the two caps tightly together, and the protective coverings are firmly bound and held between the liner and the flanges of the caps, as shown in Fig. 2.

Preferably I run a wire 15 around the finished case, which fills up the slight depression where the two halves of the covering and the two caps come together, and also serves as an additional holding means for the coverings. The wire can be held in place by the guard 10 of the tape aperture and by small ears or clinchers (not shown) pierced out of the liner on each side of the tape aperture. The guard 10 for the

tape aperture is then placed in position in the usual manner, and the tape drum and tape inserted within the case.

An additional advantage of my improved case is that a variety of materials can be used for the protective covering with satisfactory results. As there are not threads to pull out, such materials as artificial leather and cloth can be used to advantage.

10. What I claim is:—

1. A case for the uses described, comprising two flanged caps, a liner U-shaped in cross section, and ears struck up from the faces of the caps to secure the caps to the liner.

2. A case for the uses described, comprising two flanged caps, a liner, means for securing said caps to said liner, protective coverings for said caps held in place between the cap flanges and the liner, and a binding wire encircling the finished case at the point where the two caps come together.

3. A case for the uses described comprising two flanged caps, a liner U shaped in cross section, means interlocking said cap and said liner, and a covering for each cap secured in place between the cap and the liner.

4. A case for the uses described comprising two flanged caps, a liner U shaped in cross section, means on said caps engaging said liner and securing the caps thereto, a covering for each cap, the edge of each covering being firmly held between a cap flange and the liner.

5. A case for the uses described comprising two flanged caps, a liner U shaped in cross section, ears struck up from the faces of the caps to secure the caps to the liner, and a protective covering on each cap

firmly held between the cap flange and the liner.

6. A case for the uses described comprising two caps, a liner, a covering for each cap, the edge of each covering being held between a cap and the liner, and means independent of said covering holding means for securing said caps together. 45

7. A case for the uses described comprising two flanged caps, a liner, a covering for each cap, the edge of each covering being folded over a cap flange and held between said flange and the liner, and separate means for holding said caps together. 50

8. A case for the uses described, comprising two flanged caps, a liner, a covering for each cap, the edge of each covering being folded over the edge of a cap flange, whereby when the caps are placed on the liner the edges of the coverings will be held between the liner and the cap flanges, and separate means for securing said caps to said liner. 55

9. A case for the uses described, comprising two flanged caps adapted to fit together at their flanged edges to form a drum, protective coverings on said caps, gripping means within said drum to grip and hold in place said coverings, and means independent of said gripping means for holding said caps together. 60

10. A case for the uses described, comprising two flanged caps, a liner, a protective covering on each cap held in place between the cap and the liner, and means independent of said covering holding means for securing said caps to said liner. 65

In witness whereof, I have signed my name to the foregoing specification.

JOSIAH T. TAYLOR.
